CLAIM

We claim the ornamental design for a powered ratchet, as shown and described.

DESCRIPTION

FIG. 1 is a perspective view of a powered ratchet, showing our new design.

FIG. 2 is a left side view of the powered ratchet of FIG. 1.

FIG. 3 is a right side view of the powered ratchet of FIG. 1.

FIG. 4 is a front view of the powered ratchet of FIG. 1.

FIG. 5 is a rear view of the powered ratchet of FIG. 1.

FIG. 6 is a top view of the powered ratchet of FIG. 1; and,

FIG. 7 is a bottom view of the powered ratchet of FIG. 1. The broken line showing of powered ratchet is included for the purpose of illustrating portions of the powered ratchet and forms no part of the claimed design.

1 Claim, 4 Drawing Sheets
